Primary Examiner — Vy N Koenig*Assistant Examiner* — Omeed Agilee(74) *Attorney, Agent, or Firm* — Edell, Shapiro & Finn, LLC(57) **CLAIM**

The ornamental design for a nail polish bottle with cap, as shown and described.

DESCRIPTION

FIG. 1 is a front, right perspective view from above of a nail polish bottle with cap showing the new design;
 FIG. 2 is a front elevation view of the nail polish bottle with cap of FIG. 1;

FIG. 3 is a rear elevation view of the nail polish bottle with cap of FIG. 1;

FIG. 4 is a right side elevation view of the nail polish bottle with cap of FIG. 1;

FIG. 5 is a left side elevation view of the nail polish bottle with cap of FIG. 1;

FIG. 6 is a top plan view of the nail polish bottle with cap of FIG. 1;

FIG. 7 is a bottom plan view of the nail polish bottle with cap of FIG. 1; and,

FIG. 8 is front, right perspective view from below of the nail polish bottle with cap of FIG. 1.

The broken lines in the drawings depict portions of the nail polish bottle with cap that form no part of the claimed design.

1 Claim, 7 Drawing Sheets(56)
